UNITED STATES PATENT OFFICE.

JACOB HEESS, OF EBERTSHEIM, GERMANY, ASSIGNOR TO THE FIRM OF ED. MANN & CO., OF EBERTSHEIM, RHEIN-PFALZ, GERMANY.

APPARATUS FOR SORTING AND CLEANING WASTE PAPER, RAGS, AND THE LIKE.

1,035,345.

Specification of Letters Patent. Patented Aug. 13, 1912.

Application filed May 8, 1911. Serial No. 625,932.

To all whom it may concern:

Be it known that I, JACOB HEESS, a citizen of the Kingdom of Bavaria, residing at Ebertsheim, Rhein-Pfalz, Germany, have 5 invented certain new and useful Improvements in Apparatus for Sorting and Cleaning Waste Paper, Rags, and the Like, of which the following is a specification.

The subject-matter of this invention is an 10 improved apparatus for sorting and cleaning waste paper, rags and the like, which comprises, on the one hand, a longitudinally reciprocating perforated channel or screen which slants downward toward its front dis- 15 charging end and is carried by suspension springs which are likewise arranged slant- wise, and, on the other hand, a dust cham- ber below and extending the entire length of the same, from which the dust collected 20 therein is sucked away. This construction of the apparatus causes the material which is to be sorted to be cleaned very well from dust and other small particles because, owing to the described mode of suspending 25 the screen, the latter is simultaneously oscil- lated to and fro, and moved upward, so that the material to be sorted is moved forward in a hopping motion from the upper end of the screen to the lower. The removal of the 30 dust from the material to be sorted is aided by the suction chamber provided below the screen sucking away and removing the dust which is subsequently sucked away further at the lowest part of the suction chamber 35 by a fan or the like.. The screen is prefer- ably suspended by means of the springs from the frame of the apparatus in such manner that its slanting position can be adjusted as desired, whereby the feed of the 40 material to be sorted can be regulated as desired.

One form of apparatus according to the invention is represented in Figure 1 in side elevation and in Fig. 2 in plan on the accom- 45 panying drawing.

Referring to the drawing four springs *b*, *e. g.* of wood, which slant toward the front end of the screen *c* are adjustably attached by means of the brackets *f* to the four stand- 50 ards *a* connected with one another at their top ends by tie rods *a'*. To the bottom ends of the springs *b* is attached the forwardly-inclined shaking screen *c* below which the suction or dust chamber *d* is arranged. The

front, lower end of the dust chamber *d* is 55 connected by a short pipe *g* and a flexible tube *h* with a fan *i* whose pressure pipe leads to a dust-collector or into the open air. The screen is rapidly reciprocated through the medium of the connecting-rods *k* by two 60 eccentrics *e* on the common driving shaft *l* and simultaneously moves rapidly up and down.

The material to be sorted, such as waste paper, rags or the like, is thrown onto the 65 upper end of the screen and after being cleaned is thrown off at its lower end. The dust which collects in the chamber *d* when the screen is set in motion is sucked away by the fan *i*, while other small foreign bodies, 70 such as stones, pieces of iron and the like, in the material to be sorted collect in the tube *h* or in the front end of the dust chamber and must be removed therefrom from time to time. 75

I claim:-

1. A hand sorting and cleaning apparatus for waste paper, rags and the like, comprising in combination, a screen for receiving the material to be sorted and having its upper portion exposed and freely accessible to the hand of the operator, spring suspension means for said screen, means for reciprocating said screen, and means for maintaining a downward current of air through the ma- 80 terial and said screen whereby dust is con-veyed away from the eyes of the operator, substantially as and for the purposes set forth. 85

2. A hand sorting and cleaning apparatus 90 for waste paper, rags and the like, comprising in combination, a screen for receiving the material to be sorted and having its upper portion exposed and freely accessible to the hands of the operator, suspension means 95 for said screen, means for reciprocating said screen, and means for drawing air currents downwardly through said material and screen whereby dust is conveyed away from the eyes of the operator, substantially as and for the purposes set forth. 100

3. In apparatus for sorting and cleaning waste paper, rags and the like, the combination, with the frame, of suspension springs mounted thereon, a screen carried by said 105 springs, a dust-chamber directly under and attached to the screen, means for producing a suction effect connected with said dust-

- chamber, and means for longitudinally reciprocating the screen.
4. In apparatus for sorting and cleaning waste paper, rags and the like, the combination, with the frame, of slanting suspension springs mounted thereon, a forwardly slanting screen carried by said springs, a dust-chamber extending the entire length of the screen directly under and attached to the same, means for producing a suction effect connected with said dust-chamber, and means for longitudinally reciprocating the screen.
5. In apparatus for sorting and cleaning waste paper, rags and the like, the combination, with the frame, of slanting suspension springs adjustably mounted thereon, a forwardly slanting screen carried by said springs, a dust-chamber extending the entire length of the screen directly under and attached to the same, means for producing a suction effect connected with said dust-
- chamber, and means for longitudinally reciprocating the screen.
6. A hand sorting and cleaning apparatus for waste paper, rags and the like, comprising in combination, a screen for receiving the material to be sorted and having its upper portion exposed and freely accessible to the hands of the operator, suspension means for said screen, a dust chamber below said screen, means for reciprocating said screen, and means for drawing air downwardly through said screen and dust chamber to convey the dust away from the eyes of the operator, substantially as and for the purposes set forth.

In testimony whereof I affix my signature in presence of two witnesses.

JACOB HEESS.
